CLAIM

The ornamental design for an automated teller machine with
locational LED side bar lights, as shown and described.

DESCRIPTION

FIG. 1 is a perspective view of an automated teller machine
with locational LED side bar lights showing our new design;

FIG. 2 is a front elevational view thereof;

FIG. 3 is a top plan view thereof;

FIG. 4 is a bottom plan view thereof;

FIG. 5 is a right side elevational view thereof, the left side
view being a mirror image; and,

FIG. 6 is an enlarged front view of portion 6 encircled in FIG.

2.

The broken lines shown in the drawings represent portions of
the automated teller machine with locational LED side bar
lights that form no part of the claimed design.

All surfaces not shown form no part of the claimed design.
